UNITED STATES PATENT OFFICE.

WARD S. IRELAND, OF ST. LOUIS, MISSOURI, ASSIGNOR TO NATIONAL SHORTHAND MACHINE COMPANY, OF ST. LOUIS, MISSOURI, A CORPORATION OF DELAWARE.

TYPE-WRITING MACHINE.

1,292,787.

Specification of Letters Patent. Patented Jan. 28, 1919.

Application filed December 8, 1917. Serial No. 206,180.

To all whom it may concern:

Be it known that I, WARD S. IRELAND, a citizen of the United States of America, a resident of the city of St. Louis, State of Missouri, have invented certain new and useful Improvements in Type-Writing Machines, of which the following is a full, clear, and exact description, reference being had to the accompanying drawings, 10 forming a part of this specification.

My invention relates to improvements in typewriting machines. Prior to this invention typewriting machines, especially shorthand machines, have been provided with 15 means for feeding a continuous strip of paper which usually unwinds from a roll and passes to printing devices, whereby the characters are printed line by line. Owing to the peculiar requirements of a shorthand 20 machine, it is a decided advantage to use a very long strip of paper so that the writing may be continued for a considerable period of time without frequent interruptions. However, considerable difficulty has 25 been experienced in handling such paper after it passes from the machine.

One of the objects of my invention is to produce a shorthand machine having a very desirable key-actuated cutting device where- 30 by the long strip of paper is divided into relatively short sections, the present invention being an improvement on the structure shown and claimed in an application for patent on improvements in typewriting ma- 35 chines, filed by me Nov. 18, 1916, Serial No. 132,071.

A further object is to produce a shorthand machine having an automatic cutting device whereby the paper is divided into 40 uniform sheets after it passes from the printing device; in combination with means for rendering the automatic cutting device ineffective to allow the machine to be operated continuously without actuating the 45 cutting device. This enables the machine to be used indefinitely without cutting the paper. The machine herein shown is also provided with a cutting key, under the control of the operator, whereby the cutting 50 device may be actuated to cut the paper at

any time. The cutting key may be actuated without in any way disarranging the automatic mechanism. It will be important to note that the cutting key may be operated by hand when the automatic operating means is ineffective. The paper may then be cut and filed at the will of the operator, this being an advantage under some conditions. For example, in writing letters the paper may be cut and filed by actuating 55 the filing key when the dictation of a letter is completed. In this event, each letter will appear on an individual sheet, instead of being continued from one sheet to another. 60

If desired, consecutive numbers may be 65 printed at regular intervals on the long strip of paper, and these numbers will constitute page numbers for the severed sheets. The automatic operating means is so timed that a page number will appear on each 70 sheet, and since the cutting key is independent of the automatic operating means, the paper can be cut at any time without changing the relation between the numbered strip of paper and the automatic operating means. 75

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims 85 hereunto appended.

Figure I is a plan view, partly in section, of a shorthand machine constructed in accordance with my invention.

Fig. II is a side elevation of the machine, 90 one of the side walls of the housing being broken away to show the means for actuating the cutting device.

Fig. III is a detail view, on a small scale, showing the paper supply, a portion of the 95 strip of paper being unwound from the supply roll.

Fig. IV is a longitudinal section of the machine.

Fig. V is a vertical section taken ap- 100

proximately on the line V—V, Fig. IV, showing the cutting device at the rear of the machine.

Fig. VI is a detail view of the paper feeding roll.

Fig. VII is a section taken approximately on the line VII—VII, Fig. VI, showing the driving clutch whereby a step by step movement is imparted to the paper feeding roll.

Fig. VIII is a section taken approximately on the line VIII—VIII, Fig. VI, showing the retaining clutch associated with the paper feeding roll to prevent retrograde movement.

To illustrate the invention, I have shown a shorthand machine provided with printing keys 1 secured to key levers 2, the latter being pivotally supported by a pivot rod 3 (Fig. IV). Each key lever 2 is provided at its rear end with an upwardly extending printing hammer 4 adapted to coöperate with a type bar 5 having type characters 6 on its bottom face. An inking ribbon 7 passes between the type bar 5 and the printing hammers 4. Each key lever 2 is arranged directly below a restoring spring 8 (Fig. IV), and the restoring springs yieldingly hold the key levers in their non-printing positions. The strip of paper 9 (Fig. IV) passes downwardly from a supply roll 10, under a small paper straightening rod 11, thence upwardly and over a paper feeding roll 12, downwardly through an inclined passage-way 13, and then rearwardly to a cutting device near the rear end of the machine. The paper travels between the printing hammers 4 and inking ribbon 7 before it reaches the cutting device.

When a printing key is depressed, its key lever 2 turns about the axis of the pivot rod 3 (Fig. IV), and the printing hammer 4, at the rear of the key lever, moves upwardly to force a portion of the paper onto the inking ribbon 7, at the same time forcing the ribbon onto one of the type characters 6. The printing keys may be operated independently of each other to print selected characters, and several keys may be operated simultaneously to print a line of characters, as is well understood in this art. The characters are usually printed line by line, a complete word or syllable being printed during each key operation. The strip of paper is, therefore, advanced one step during each key operation.

The paper feeding device comprises a universal bar 14 (Fig. IV) arranged over the key levers at a point in front of the printing hammers 4 and fixed to a bell crank lever 15, the latter being pivotally supported by the pivot rod 3. The upwardly extending arm of this bell crank lever 15 is notched to receive a pin 16 (Figs. IV, VI and VII) projecting from the oscillatory drive mem-

ber 17 of a paper feeding clutch. This drive member 17 is loosely mounted in a driven clutch member 18, the latter being secured to one end of the paper feeding roll 12. The drive member 17 oscillates freely in response to the movements of the universal bar, so as to impart a step by step movement to the paper feeding roll. When the oscillatory drive member 17 turns in the direction indicated by the arrow in Fig. VII, the small spring pressed rollers 19 are firmly clamped in the tapering or wedge-shaped spaces between said drive member and the driven clutch member 18. Movement is then transmitted from the universal bar, through the drive member 17 and rollers 19, to the driven clutch member 18. The paper feeding roll 12 is secured to the driven clutch member 18 (Figs. VI and VII), so as to advance one step when the oscillatory drive member 17 turns in the direction indicated by the arrow in Fig. VII. During the reverse movement, when the drive member 17 moves oppositely to the direction indicated by the arrow in Fig. VII, the small rollers 19 tend to move into the wide ends of the tapering spaces, and they do not transmit movement to the driven clutch member 18. In response to the oscillatory movements of the universal bar and drive clutch member 17, the paper feeding roll 12 turns step by step in the direction indicated by the arrow in Fig. VII.

To positively prevent retrograde movement, a stationary clutch member 17' (Figs. VI and VIII) is arranged within a rotary clutch member 18', secured to one end of the paper feeding roll 12. A pin 20 extending from the stationary clutch member 17', is secured to a stationary side frame 21. Spring pressed rollers 19' are arranged in the wedge-shaped spaces between the stationary clutch member 17' and the rotary clutch member 18'. These small rollers 19' allow the feed roll to turn in the direction indicated by the arrows in Figs. VII and VIII, but if an effort is made to reverse the direction of movement, the small rollers 19', by tending to move toward the points of the wedge-shaped spaces, will coöperate with the stationary clutch member 17' to prevent such retrograde movement.

To illustrate the preferred form of the invention, I have shown an automatic cutting device including blades 26 and 27 located at points on opposite sides of the path of the paper and adapted to sever the paper after it passes from the printing, uncurling and feeding device. The blade 26 is closely fitted to an arcuate seat on an oscillatory blade holder 28. The arcuate blade 26 is secured to the blade holder 28, as shown most clearly in Fig. IV. A filing pin 29 (Fig. IV), located below the oscillatory blade holder 28,

is arranged to receive the small sections of paper severed by the blades 26 and 27. The oscillatory blade holder 28 is preferably recessed at 30 (Fig. IV) to receive the filing pin 29. When this blade holder moves downwardly from the position shown in Fig. IV, the blades 26 and 27 coöperate with each other to cut the paper, and the blade holder 28 forces the severed piece of paper onto the filing pin 29.

The blade 27 is preferably secured to an arm 31 (Fig. IV), the latter being pivoted at 33. A spring 34, connected to the arm 31, tends to force the blade 27 into the path of the arcuate blade 26. When the blade 26 occupies the elevated position shown in Figs. IV and V, an extension 35 projecting downwardly from said blade is engaged by the spring pressed blade 27.

20 The cutting device may be operated in response to movements of the printing keys, and it is preferably constructed to automatically cut the paper into a series of short uniform sheets.

25 Briefly stated, the automatic cutting device comprises an operating spring for moving the blade holder 28, means for transmitting energy from the printing keys to said operating spring, so as to place the latter under the required degree of tension, and a restoring spring for returning the blade holder 28. The operation of the filing device is controlled by a timing device which moves step by step in response to movements of the 30 printing keys, and upon the completion of a predetermined number of key operations, the timing device reaches a position wherein it will permit the operating spring to actuate the movable blade holder 28, at the same 35 time placing the restoring spring under tension.

Journals 36 and 36', extending from the ends of the oscillatory blade holder 28 (Figs. I, II and IV) are mounted in suitable bearings, and an operating arm 37 is secured to the journal 36. A restoring spring 38 (Fig. II) tends to retain the arm 37 in engagement with an abutment 39, and this restoring spring normally holds the oscillatory blade holder in an elevated position above the path of the paper. A trippable operating member 40 (Fig. II) is provided with a projection 41 adapted to strike an abutment 42 on the arm 37. This trippable member 40 is pivotally connected to a long power transmission lever 43, the latter being pivotally supported at 44 and provided with an abutment 45 which engages a timing cam 46. 47 designates an operating spring (Fig. I) connecting the lever 43 to a stationary part of the machine. The timing cam 46 moves step by step in response to operations of the printing keys, as will be hereinafter described, thereby transmitting power through

the long lever 43 and gradually increasing 65 the tension of the operating spring 47. When the shoulder 46', on the timing cam 46, reaches the corner 45' of the abutment 45, the operating spring 47 pulls the trippable operating member 40 downwardly, 70 thereby causing the projection 41 to strike the abutment 42 on the arm 37. This causes the arm 37 to turn about the axis of the journal 35 to which it is secured, and since the movable blade holder 28 is also fixed to said 75 journal, the blade holder will move downwardly to sever the paper and to force the severed sheet onto the filing pin 29. The restoring spring 38 is placed under tension during the filing operation, however, this 80 spring is not effective until the trippable operating member 40 is disengaged from the abutment 42 on the arm 37. The means for releasing the trippable member 40 (Fig. II) comprises a cam face 48 formed on said member 40 and engaging a roller 49. 50 designates a spring connecting the trippable member 40 to a stationary part of the machine, and tending to force the cam face 48 into engagement with the roller 49. During the 90 downward movement of the trippable member 40 its cam face 48 moves along the roller 49, so as to release said trippable member from the abutment 42 on the arm 37, thus permitting the restoring spring 49 to re- 95 turn the arm 37 and movable blade holder 28, the latter being provided with the journal 36 to which the arm 37 is secured. The operating spring 47 (Fig. II) is of sufficient strength to actuate the cutting device and 100 at the same time place the restoring spring 38 under tension.

Fig. II illustrates the automatic mechanism as it appears immediately before the cutting operation, the shoulder 46' on the 105 timing cam 46 being located very close to the corner 45' on the lever 43, and the trippable operating member 40 being so high that its projection 41 lies above the abutment 42. When this operating mechanism 110 is released by the timing cam 46, the trippable operating member 40 is pulled downwardly by the operating spring 47 until the stop finger 51 (Fig. I) on the lever 43 engages a padded abutment 52. The trippable 115 operating member 40 then occupies its lowest position, and the spring 38 is permitted to restore the arm 37 very quickly. Thereafter the timing cam 46 continues to turn in response to the key operations, and the 120 long power transmission lever 43 is actuated to gradually lift the trippable operating member 40, the latter moving upwardly until its projection 41 lies directly above the abutment 42.

The means for actuating the timing cam 46 includes a large gear wheel 53 (Figs. I and II) fixed to the timing cam, and a pinion

- 54 meshing with said large gear wheel. The pinion 54 is secured to a shaft 55 projecting from one end of the paper feeding roll 12. This shaft 55 is shown in Figs. I, II and IV.
- 5 It will now be understood that motion is transmitted from the key levers, through the universal bar, paper feeding device, pinion 54, and thence through the gear wheel 53 to the timing cam 46. The timing cam, 10 therefore, advances one step in response to each key operation, and since said cam is operated through the medium of the paper feeding device, it will be apparent that the filed sheets will be uniform in length.
- 15 When it is desirable to operate the machine continuously without cutting the paper, the operator can render the automatic operating means ineffective by locking the long transmission lever 43 (Fig. II) in an inoperative 20 position. This is accomplished by forcing a hook-shaped latch 59 (Fig. II) into inoperative engagement with a pin 60 on the lever 43. A finger 61, extending downwardly from the lever 43, may be engaged 25 and manipulated to locate the pin 60 at a point near the hook at the upper end of latch 59, and the latter may then be manipulated to coöperate with the pin 60 in holding the lever 43 in an inoperative position. The 30 timing cam 46 may then be rotated continuously without in any way affecting the cutting device. A spring 62 normally holds the latch 59 in the position shown in Fig. II, and when this latch is hooked onto the 35 pin 60 it may be easily released by moving the finger 61 downwardly, thus moving the pin 60 downwardly and permitting the spring 62 to restore the latch 59 to the position shown in Fig. II.
- 40 A cutting key 63 (Figs. I and II) may be operated at any time to cut and file the paper, without in any way disarranging the automatic mechanism. The cutting key I have shown is in the form of a bell crank 45 lever pivoted at 64 and connected by means of a link 65 to a crank 66, the latter being loosely mounted on the journal 36. The movable blade holder 28 is fixed to this journal 36. When the cutting key 63 is de-
- 50 pressed, motion is transmitted through the link 65 and crank 66 to the operating arm 37, thereby actuating the movable blade holder, as will be hereinafter more fully described, to cut the paper and to force the 55 severed sheet onto the filing pin 29.
- When the latch 59 (Fig. II) is engaged with pin 60 to hold the lever 43 in an inoperative position, the trippable operating member 40 is located in an elevated position, 60 where it will not prevent the cutting device from being actuated by the cutting key 63. The cutting key can also be actuated at any time when the automatic mechanism is in its operative condition. The operating arm 37 on the journal 36 (Fig. II)

is actuated by the cutting key 63, and the restoring spring 38 is utilized to restore the movable blade holder when the cutting key is released. A restoring spring 65' tends to retain the cutting key in the position shown in Fig. II.

If the cutting key is actuated when the projection 41, on the trippable operating member 40, is in the path of the abutment 42, the latter in moving downwardly 75 will strike the projection 41 and force it out of the way. During the return stroke of the oscillatory arms 37 and 66, a cam 67 carried by the loose crank arm 66 will move upwardly in advance of the abutment 42 so 80 as to prevent the latter from being stopped by the projection 41. When the cutting key is actuated, the lower portion of cam 67 engages the abutment 42 to transmit movement to the operating arm 37. It is 85 to be understood that the cam 67 on the loose crank arm 66 performs no function when the cutting device is actuated by the automatic mechanism, and if the cutting key 63 is actuated when the automatic mechanism is in the position shown in Fig. II, the cam 67 will perform no useful function. However, if the cutting key is actuated when the projection 41 lies below and in the path of abutment 42, the abutment 41 must 90 be shifted and held out of the way to permit the abutment 42 to return to its normal position, and this shifting operation is performed by the cam 67.

The strip of paper 9 which unwinds from the roll may be provided with consecutive numbers at regular intervals, as shown in Fig. III. The dotted lines in this view do not appear on the paper; they merely indicate the points at which the paper is to be 100 severed by the automatic cutting device. The consecutive numbers on the paper serve as page numbers for the small sheets, and if the sheets are accidentally disarranged, the page numbers will clearly indicate the order 105 in which they are to be replaced. When the paper is properly arranged in the machine, the cutting elements of the automatic cutting device will sever the paper at the points indicated by dotted lines (Fig. III) as previously suggested, and a page number will 110 appear on each sheet. It is sometimes desirable to cut the paper by hand, while the automatic device is in its operative condition, and this hand operation may be performed by means of the cutting key 63 without moving the timing cam 46. When the timing device is set to cut the paper at the predetermined points, the cutting key may 115 be actuated at irregular intervals, and these cutting operations will not prevent the automatic device from continuing to cut the paper at the predetermined points. The cutting key can be actuated at any time 120 without changing the relation between the 125 130

numbered strip of paper and the timing device.

The hand operated cutting means, including the cutting key 63, is claimed in an application for patent filed by me on Dec. 8, 1917, Serial Number 206,181. The filing device is claimed in an application filed by me on Dec. 8, 1917, Serial Number 206,179. The paper feeding device is claimed in an application filed by me on May 19, 1917, Serial Number 169,621. The paper straightening means including the small rod 11, is claimed in an application filed by me on May 19, 1917, Serial Number 169,620. The printing elements comprising the key levers and the details of construction in the key lever mounting, are claimed in an application filed by me on Dec. 8, 1917, Serial Number 206,182.

20 I claim:—

1. In a typewriting machine adapted to receive a strip of paper, a paper feeding device, a printing device, keys for operating said printing device, an automatic cutting device whereby the paper is divided into sections after it passes from said printing device, and means for rendering said automatic cutting device ineffective.

2. In a typewriting machine adapted to receive a strip of paper, a printing device, a cutting device for dividing the strip of paper into sections after it passes from said printing device, a paper feeding device for feeding the paper to said printing device and then to said cutting device, printing keys whereby said printing device and paper feeding device are actuated, automatic means for transmitting movement from said printing keys so as to actuate said cutting device upon the completion of a number of key operations, thereby dividing the strip of paper into approximately uniform sections, and means for rendering said automatic means ineffective so as to allow the printing keys to actuate said paper feeding device continuously without actuating said cutting device.

3. In a typewriting machine adapted to receive a strip of paper, a printing device, a cutting device for dividing the strip of paper into sections after it passes from said printing device, a paper feeding device for feeding the paper to said printing device and then to said cutting device, printing keys whereby said printing device and paper feeding device are actuated, automatic operating means including a transmission member through which power is transmitted from said keys to actuate said cutting device, and means for rendering said transmission member ineffective so as to allow said keys to actuate said printing device and paper feeding device continuously without actuating said cutting device.

4. In a typewriting machine adapted to

receive a strip of paper, a printing device, a cutting device for dividing the strip of paper into sections after it passes from said printing device, a paper feeding device for feeding the paper to said printing device and then to said cutting device, printing keys whereby said printing device and paper feeding device are actuated, automatic operating means including a transmission member through which power is transmitted from said keys to actuate said cutting device, and means for holding said transmission member in an inoperative position so as to allow said keys to actuate said printing device and paper feeding device continuously without actuating said cutting device.

5. In a typewriting machine adapted to receive a strip of paper, a printing device, a cutting device for dividing the strip of paper into sections after it passes from said printing device, a paper feeding device for feeding the paper to said printing device and then to said cutting device, printing keys whereby said printing device and paper feeding device are actuated, automatic operating means including a cam and lever through which power is transmitted from said keys to actuate said cutting device, and means for holding said lever in an inoperative position so as to allow said keys to actuate said cam without transmitting movement to said lever.

6. In a typewriting machine adapted to receive a strip of paper, a printing device, a cutting device for dividing the strip of paper into sections after it passes from said printing device, a paper feeding device for feeding the paper to said printing device and then to said cutting device, printing keys whereby said printing device and paper feeding device are actuated, automatic operating means including a transmission member through which power is transmitted from said keys to actuate said cutting device, and a latch for holding said transmission member in an inoperative position so as to allow said keys to actuate said printing device and paper feeding device continuously without actuating said cutting device.

7. In a typewriting machine adapted to receive a strip of paper, a printing device, a cutting device for dividing the strip of paper into sections after it passes from said printing device, a paper feeding device for feeding the paper to said printing device and then to said cutting device, printing keys whereby said printing device and paper feeding device are actuated, automatic means for transmitting movement from said printing keys so as to actuate said cutting device upon the completion of a number of key operations, thereby dividing the strip of paper into approximately uniform sections, means for rendering said automatic means ineffective so as to allow the printing keys

- to actuate said paper feeding device continuously without actuating cutting device, and auxiliary operating means including a cutting key whereby said cutting device is actuated when the automatic means is in its ineffective condition.
8. In a typewriting machine adapted to receive a strip of paper, a printing device, a paper feeding device, printing keys for operating said printing device and paper feeding device, a cutting device for cutting the strip of paper into relatively small sections, automatic operating means, operated by said keys, whereby said cutting device is actuated automatically to cut the paper into uniform sections, and auxiliary operating means for actuating said cutting device, said auxiliary operating means being free to move independently of said automatic operating means.
10. In a typewriting machine adapted to receive a strip of paper, a printing device, a paper feeding device, printing keys for operating said printing device and paper feeding device, a cutting device for cutting the strip of paper into relatively small sections, automatic operating means, operated by said keys, whereby said cutting device is actuated automatically to cut the paper into uniform sections, and auxiliary operating means, including a cutting key for actuating said cutting device, said cutting key being free to move independently of said automatic operating means.
12. In a typewriting machine adapted to receive a strip of paper, a printing device, a paper feeding device for feeding the paper to and from said printing device, keys for operating both of said devices, a cutting device for cutting the strip of paper into relatively small sections, said cutting device including an operating member provided with an abutment, automatic means, operable by said keys, whereby the cutting device is actuated at regular intervals, said automatic means including a trippable operating member adapted to strike said abutment, and auxiliary operating means whereby the cutting device may be actuated independently of said automatic means, said auxiliary operating means including a device whereby the trippable operating member is shifted away from the path of said abutment.
14. In a typewriting machine adapted to receive a strip of paper, a printing device for printing lines of characters on the paper, keys for actuating said printing device, a paper feeding device for feeding the strip of paper step by step to and from said printing device, a cutting device for cutting the strip of paper into relatively small sections, and means for transmitting movement from said paper feeding device to said cutting device, so as to divide the paper into uniform sections in response to movements of said paper feeding device.
16. In a typewriting machine adapted to receive a strip of paper, a printing device for printing lines of characters on the paper, printing keys for actuating said printing device, a paper feeding device for feeding the strip of paper step by step to and from said printing device, a cutting device for dividing the strip of paper into relatively small sections, means for transmitting movement from said keys to said paper feeding device, and means for transmitting movement from said paper feeding device to said cutting device so as to actuate said cutting device automatically in response to movements of said keys and paper feeding device.
18. In a typewriting machine adapted to receive a strip of paper, a printing device for printing lines of characters on the paper, printing keys for actuating said printing device, a paper feeding device for feeding the strip of paper step by step to and from said printing device, a cutting device for dividing the strip of paper into relatively small sections, and automatically operating means including speed-reducing gearing through which movement is transmitted from said printing keys to actuate said cutting device.
20. In a typewriting machine adapted to receive a strip of paper, a printing device for printing lines of characters on the pa-

per, printing keys for actuating said printing device, a paper feeding device for feeding the strip of paper step by step to and from said printing device, a cutting device 5 for dividing the strip of paper into relatively small sections, and automatically operating means including speed-reducing gearing through which movement is transmitted from said printing keys to actuate

said cutting device, said speed reducing 10 gearing including a pinion driven through the medium of said paper feeding device and a relatively large gear wheel meshing with said pinion.

In testimony that I claim the foregoing 15 I hereunto affix my signature.

WARD S. IRELAND.
